UNITED STATES PATENT OFFICE.

STEWART V. VAN BERSCHOT, OF CHICAGO, ILLINOIS.

WINDOW VENTILATOR.

Application filed April 26, 1926. Serial No. 104,729.

My invention relates to a window ventilator and pertains more specifically to a combined window-sill and ventilator structure that is made so that a window may be raised slightly from the sill and the sill plate moved on a hinge in an upward direction so that a direct or straight draft through the open portion of the window is thereby prevented. The structure I have 10 designed affords a dependable ventilator and when the same is closed down flat will provide the usual sill for the window so that it avoids the use of an additional frame such as is usually employed for window ventilators which have to be removed and stored away when not in use. Among the objects which I have in mind in designing my improved window-sill and ventilator are dependability in operation, compactness in arrangement and disposition of parts, novelty 20 in construction and economy in manufacture.

I prefer to carry out my invention in substantially the manner hereinafter fully described and as more particularly pointed out in the claims, reference being made to the accompanying drawings that form a portion of this specification.

In the drawings:—

30 Figure 1 is a perspective of a window frame and sash showing my improved sill and ventilator in use, the sill being shown in a raised position for the purpose of ventilation.

35 Figure 2 is a top plan of one end of the sill showing the ventilator closed to provide a flat sill, the window being shown in horizontal section.

40 Figure 3 is a transverse vertical section on the line 3, 3 of Figure 2 looking in the direction of the arrows and showing the sill partially raised for the purpose of ventilation.

45 In the drawings, which are in a sense schematic for the purpose of illustrating a preferred or typical embodiment of my invention, I have employed similar reference characters to designate like parts wherever they appear throughout the several views.

50 Referring to Figure 1, it will be seen I have adapted my device to window frame and sash of the ordinary construction, with the exception that the standard sill is modified to the extent of providing the same with 55 a tiltable plate 1 that is hinged along its edge nearest the window sash by means of

butt hinges 2 so that the inner edge of the plate 1 which is inside or farthest from the window, may be raised or lowered as desired. About midway of each end edge of the plate 60 it is provided with a small bolt 4 that projects outwardly from said edges and is provided upon its outer threaded end with a thumb-nut 3. A slotted or strut brace 5 cooperates with the shank of the bolt 4 and at 65 one of its ends is pivotally mounted upon a lateral stud 7 projecting from the bracket or mounting plate 6 that is secured to the adjacent portion of the window-sill base. As seen in Figure 1, there are two of these 70 brace structures, one at each end of the plate 1. The window-sill 8 has a cut-out recess or depression 9 of substantially a depth corresponding with the thickness of the sill plate 1 and of substantially the same 75 shape and dimensions as the plate so that when the latter is lowered and out of use it will seat in the depression and lie flush with the upper surface of the sill so that a neat appearance is presented. The brackets 80 6 are secured to the transverse end edges of the recess and there are provided small notches or offsets 10 adjacent thereto for the purpose of receiving the thumb-nut 3 and any projecting portion of the shank of 85 bolt 4.

When it is desired to ventilate with fresh outside air, the window may be raised a few inches above the sill and the plate 1 is then raised upon its hinges 2 into any desired 90 inclined position as suggested in Figures 1 and 3 where it is maintained by tightening the thumb-nuts 3 against the outer surface of the brace or strut 5. The slot in the brace or strut 5 extends to adjacent the end 95 thereof, thereby permitting of a wide range of adjustability and it also thereby prevents the ventilator plate being raised to such an extent that it might fall outwardly into engagement with the glass or window pane and 100 damage the same. When it is not desired to use the plate 1 as a ventilator, the thumb-nuts 3 are loosened and the plate is lowered flat in the recess of the sill, where said plate and all of its parts will then be flush below 105 the plane of the top of the sill, so as to not interfere with the functioning of the structure as a window-sill. If desired, where the window-sill is comparatively narrow, the plate 1 may be divided longitudinally in 110 two parts and hinged together so as to be collapsed when the same is lowered to form

a window-sill, and it will be understood that the surfaces of the recess or depression and the faces of the plate are painted or finished in the same manner as the other portions of 5 the window frame and sash in order to harmonize with or maintain the decorative scheme of the room in which the ventilator is installed. It will be obvious that other modifications may be made without departing 10 from the principles herein disclosed and I desire it understood that all of such changes are fully contemplated as coming within the scope of my appended claims.

What I claim is:—

- 15 1. A combined window-sill and window ventilator comprising a sill having a depression therein, a plate normally disposed in said depression and hinged along its edge nearest the window, said plate adapted in its 20 normal position to provide the upper surface of the window-sill, and means for maintaining said plate in divers positions when moved upon its hinges.
- 25 2. A combined window-sill and window ventilator comprising a sill having a longitudinally elongated depression therein, a movable plate normally seated in said depression and in said position providing the upper surface of the sill, braces for maintaining 30 said plate in divers angular positions with respect to said sill and pivotally connected to one of said elements, and pin and slot adjustable connections between said braces and the other of said elements.
- 35 3. A combined window-sill and window ventilator comprising a sill, an elongated plate hinged to said sill along its longitudinal edge nearest the window, and a brace pivotally mounted at one end on the sill 40 and having its intermediate portion coacting with the plate to assist in supporting

the latter when it is moved upon its hinge, the arrangement of the brace and plate being such that the latter may be disposed flat upon the sill whereby the brace will be fitted 45 snugly at the end of the plate flush with the top thereof.

4. A combined window-sill and window ventilator comprising a sill, an elongated plate hinged to said sill along its longitudinal edge nearest the window, a projection upon an end edge of said plate, a brace pivotally connected at one end to said sill and having a slot therein that coacts with said projection, and means for clamping said 55 projection and brace together to maintain said plate at divers angles to said sill, the arrangement of the brace and plate being such that the latter may be disposed flat upon the sill whereby the brace will be fitted 60 snugly at the end of the plate flush with the top thereof.

5. A combined window-sill and window ventilator comprising a sill having an elongated depression in its upper surface, an 65 elongated plate hingedly connected to the edge of the recess nearest the window, bolts projecting from the end edges of said plate, braces pivotally connected at one end to the 70 end edges of said depression and having slots that co-operate with the shanks of said bolts, whereby to permit said plate to be moved upon its hinged edge to divers angles to the plane of the sill, and thumb-nuts 75 screwed upon the bolts and adapted to clamp against said braces and maintain said plate in its divers adjusted positions.

Signed at Chicago, in the county of Cook, and State of Illinois, this 22nd day of April, 1926.

STEWART V. VAN BERSCHOT.
